United States Patent Office

Des. 206,081
Patented Oct. 25, 1966

206,081

FOOT SOCK OR SIMILAR ARTICLE

Shepard Schwartz, ½ May Hosiery Mill, Nashville, Tenn.

Filed May 4, 1966, Ser. No. 2,156

Term of patent 14 years

(Cl. D47—7)

FIG. 1 is a perspective view of a foot sock or similar article showing my new design;

FIG. 2 is a side elevation of the foot sock in a relaxed position;

FIG. 3 is a bottom plan; and

FIG. 4 is an enlarged fragmentary view of a portion of the knit, showing the knit broken away for convenience of illustration.

I claim:

The ornamental design for a foot sock or similar article as shown and described.
